UNITED STATES PATENT OFFICE.

CHARLES W. DAKE, OF CHICAGO, ILLINOIS, ASSIGNOR TO PYLE-NATIONAL ELECTRIC HEADLIGHT COMPANY, OF CHICAGO, ILLINOIS, A CORPORATION OF NEW JERSEY.

ELECTRODE-HOLDER FOR ARC-LAMPS.

1,122,194.

Specification of Letters Patent.

Patented Dec. 22, 1914.

Application filed December 5, 1912. Serial No. 735,033.

To all whom it may concern:

Be it known that I, CHARLES W. DAKE, a citizen of the United States, residing at Chicago, in the county of Cook and State 5 of Illinois, have invented a certain new and useful Improvement in Electrode-Holders for Arc-Lamps, of which the following is a specification.

My invention relates to electrode holders 10 for arc lamps and has particular reference to means for holding electrodes where it is necessary to keep the temperature of the electrode low.

My invention is illustrated in the accompanying drawing, wherein—

Figure 1 is a vertical section through the lower electrode, being made on the line 1—1 of Fig. 2. Fig. 2 a view from above of the lower carbon and holder; Fig. 3 a cross section on the line 3—3 of Fig. 1; Fig. 4 a like cross section through a modification.

Like parts are indicated by the same letter in all the figures.

A is a standard suitably supported from 25 the base of the lamp and provided with the upwardly projecting tubular part B. This part is preferably enlarged at C and provided above and below this enlargement and on one side of the inner surface with the 30 two notched ribs D, D.

E is a wedge, shaped as shown, and having at its lower end a cross pin F, the ends of which project respectively into the inclined vertical channels G, G formed on 35 the inside of the separated parts J, J which project from the tubular portion B. The two parts J, J are connected below their upper extremities by the transverse part K, but a wide opening between them is left at 40 J so as to permit the wedge E to be lifted up, swung on its pin F in the upper part of the slots G, G and turned outwardly as indicated in the dotted lines in Fig. 1 so as to release the carbon.

E¹ is a notch in the upper end of the wedge E whereby it can be pried upwardly when it is found to be stuck or fastened in place.

L is the electrode which is adapted to be 50 held by the holder. It comprises the central core L¹ and the lateral longitudinal flanges or ribs L², L². These ribs are notched at their outer edges at L³, said notches being

preferably of equal length and adapted to register with the notches in the ribs D, D 55 on the inside of the tubular part.

In the modification shown in Fig. 4. M is an electrode of the usual round form. In this case the inner opening through the tubular part B is eccentric as indicated at 60 M¹ and has no inner ribs. The electrode is not fluted or ribbed and there are no notches. The wedge-shaped locking device E¹ is in this case slightly different in shape from that of the device shown in the other figures, 65 otherwise the parts are essentially the same.

It will be understood, of course, that very considerable modifications can be made in the form, size, proportions and arrangement of these several features, and my drawings, therefore, are in a certain sense dia- 70 grammatic, although they register an actual structure. They are intended as diagrams to illustrate the idea of them as drawings of a fixed or settled form of the 75 device.

The use and operation of my invention is as follows: Assuming that the structure is to be employed in connection with an arc lamp intended for a locomotive headlight, 80 experience shows that it is highly desirable to employ copper for the lower electrode. The temperature at which such lamps run, however, is very close to the fusing point of copper, and hence the great importance of 85 means for keeping down this temperature. Moreover, as the arc is from time to time formed, the operation involves a dropping of the upper electrode on the lower and this tends to gradually drive the lower electrode 90 down unless it be very rigidly held in position. If it be held rigidly in position by any ordinary clamping means, the heat tends to cause the parts to closely adhere so that it becomes very difficult to disengage 95 them. This, however, is essential because the copper electrode must be from time to time raised to accommodate for the wear or consumption or disintegration of the upper end of such lower electrode. My invention 100 is intended to take care of all these difficulties.

The fluted electrode is the preferred form, and in this case the edges of the flutings are notched. The notches are equidistant, or 105 of an equal length, so that if the lamp is

trimmed at comparatively regular intervals, it will only be necessary to raise the electrode by one notch to preserve comparatively uniform conditions. By having the opposed 5 surfaces of the electrodes and its holder notched, it will be possible to secure the electrode rigidly in position by clamping the opposed surfaces together. This is accomplished by the sliding wedge which I have 10 illustrated. It is only necessary to lift this wedge into the position shown in dotted lines until the electrode is put into position and then drop it back into place, whereupon it forces the two opposed notched surfaces 15 together. If, however, the parts become stuck, the wedge can be forced up by catching some tool in its upper notch and using the same as a lever to start it upwardly. The electrode if fluted presents, of course, a 20 very extended radiating surface which tends to keep down the temperature, but to get the best effects its engagement with the walls of the holder should be reduced to a minimum and this is accomplished in the preferred 25 form of my device by raising on the inner edge of the holder vertical ribs with notches to register with those of the ribs on the electrode. If, however, for any reason this portion of the invention is not important, 30 the wedge device for locking the electrode in position can be employed as indicated in Fig. 4. The wedge may be introduced from below when the electrode is not in position.

I claim:

- 35 1. The combination with an arc light electrode having fluted sides, of a holder therefor having a plurality of inwardly projecting ribs to engage the ridges thereon and to form passages up therealong, the 40 ridges and ribs being serrated and interlocking with each other, and means for holding the electrode in fixed engagement with respect to the holder.
- 45 2. The combination with an arc light electrode having fluted sides, of a holder therefor having a plurality of inwardly projecting ribs to engage the ridges thereon and to form passages up therealong, the ridges and ribs being serrated and interlocking 50 with each other, and means for holding the electrode in fixed engagement with respect to the holder; said means comprising a wedge slidably mounted in the holder and engaging one of the flutes formed in the 55 electrode to force the serrations in the elec-

trode and holder into engagement each with the other.

3. The combination with an arc light electrode having fluted sides, of a holder therefor having a plurality of inwardly projecting 60 ribs to engage the ridges thereon and to form passages up therealong, the ridges and ribs being serrated and interlocking with each other, and means for holding the electrode in fixed engagement with respect to 65 the holder, said means comprising a wedge slidably mounted in the holder and engaging one of the flutes formed in the electrode to force the serrations in the electrode and holder into engagement each with the other, 70 a guide slot in the holder, a pin located in the slot the small end of the wedge adapted to slide in the guide slot to be in position therein when the wedge is in the locking 75 position.

4. The combination with an arc light electrode having fluted sides, of a holder therefor having a plurality of inwardly projecting ribs to engage the ridges thereon and to form passages up therealong, the ridges 80 and ribs being serrated and interlocking with each other, and means for holding the electrode in fixed engagement with respect to the holder, said means comprising a wedge slidably mounted in the holder, the 85 wedge being slotted for manipulation at the end removed from the pin.

5. The combination with an arc light electrode having fluted sides, of a holder therefor having a plurality of inwardly projecting 90 ribs to engage the ridges thereon and to form passages up therealong, the ridges and ribs being serrated and interlocking with each other, and means for holding the electrode in fixed engagement with respect to 95 the holder said means comprising a wedge slidably mounted in the holder, the wedge being slotted for manipulation at the end removed from the pin, the upper wider end of the wedge projecting above the effective 100 wedge engaging portion of the holder being slotted for the introduction of a manipulating tool.

In testimony whereof, I affix my signature in the presence of two witnesses this 3rd 105 day of December 1912.

CHARLES W. DAKE.
